UNITED STATES PATENT OFFICE.

ALBERT E. DE ARMOND, OF CHICAGO, ILLINOIS.

SILO.

979,444.

Specification of Letters Patent. Patented Dec. 27, 1910.

Application filed October 4, 1909. Serial No. 520,891.

To all whom it may concern:

Be it known that I, ALBERT E. DE ARMOND, a citizen of the United States, residing at Chicago, in the county of Cook and 5 State of Illinois, have invented a certain new and useful Improvement in Silos, of which the following is a specification.

My invention relates to a silo and has for its object to provide new and useful improvements relating thereto.

It is illustrated in the accompanying drawings, wherein—

Figure 1 is a cross section through a silo containing my invention; Fig. 2, a horizontal detail section; Fig. 3, a horizontal detail section through a modification; Fig. 4, a detail cross section; Fig. 5, a detail of the connecting devices.

Like parts are indicated by the same letters in all the figures.

A is the base or bottom above which rises a circular wall surmounted by a roof. This wall is composed of a series of upright studs B preferably U-shaped. From the web portion of each of these uprights is struck out a tongue B¹ leaving the opening B² through which the tongue of the next adjacent stud projects as indicated in Fig. 4. Each of these tongues in the form shown is provided 25 with a short upwardly struck strap B³ at each end, the straps of one registering with those of another so as to leave an opening B⁴ through which may be passed the nail

B⁵ to lock the parts together. In the modified form shown in Fig. 3 the tongues are omitted and a cable C encircles the studs, being attached thereto in any desired manner.

D, D are sheets of lath material preferably in the form of metallic lathing or some 40 form of woven wire material.

E, E is the coating or covering on the interior and exterior of the wall. This finishes the circular silo wall. F, F are openings therethrough admitting air from 45 the exterior into the hollow wall.

The roof is of any desired construction and may be made of material similar to that used in the wall. This roof is preferably composed of the upper and lower shells G, 50 G¹ with the intermediate air space G². This air space connects with the air space in the circular vertical wall.

J is a tube at the top covered by the weather cap K and provided with the 55 damper L. Into it opens the roof space G².

The cable C may be used with either form

of construction shown in Figs. 2 or 3 though it is not so necessary in the case of the construction of Fig. 2, and the tongues and openings illustrated in Figs 2 and 4 may 60 be used in the structure of Fig. 3 though they are not there so necessary. The tongues are preferably bent to one side as indicated in Fig. 5 so as to make an angle in the horizontal plane with the web of the stud. This 65 is to bring the tongue through the opening of the next stud. Of course, means other than those shown could be used to secure the tongues together.

I have shown in my drawings a complete 70 form of the structure capable of practical application, but I realize that various changes could be made without departing from the spirit of my invention. I therefore wish my drawings to be taken as in a sense 75 diagrammatic and intended simply to illustrate one form of my invention and suggest others.

The upright studs could be of various structures and might consist as indicated 80 each of a single channel bar or of two outer ends or bars of any desired shape connected by any desired cross pieces, braces or webs and there might be one or more such tongues on any given horizontal section and the same 85 might be placed near either edge or at the middle of such stud and such tongue might be struck as indicated or attached in any desired manner.

The use and operation of my invention 90 are as follows: In the construction of silos it is, of course, desirable to have the thinnest possible wall and to have it vertical on both sides, and to have it ventilated. All these things I accomplish in the best possible manner by my invention. The studs are set up and supported in position in any desired manner and this is very simple if the tongues and openings are employed, for each stud is locked to the next by the tongue and the pin. At the same time, or with any other means of connecting the vertical studs together, they may be surrounded by a securing cable. This is not usually necessary 100 where the tongues are properly connected together. When the parts have been thus assembled we have a circular cage. To this inside and outside, is secured the lathing material and on that is placed the finished coating. This completes the vertical wall, the proper openings being made or left as the work progresses. The ventilating open- 105 110

ings at the outside bottom portion of the wall can be made as desired. The roof, as above suggested, is placed in position and its open space connected with the space in the 5 wall. The ventilation space in the vertical wall is preferably not otherwise connected with the interior of the silo. There is, therefore, a continuously moving current of air upwardly and outwardly through the 10 ventilation spaces in the wall and roof without using the interior of the silo as any portion of the channel for such air. The air from the silo itself assists in furnishing a draft by passing out through the tube at the 15 top. The damper L can control this passage.

I claim:—

1. A building comprising a hollow wall perforated about the outside near its bottom, a hollow roof supported upon said wall in communication with the interior thereof, a tube projecting through said roof, in communication intermediate its ends with the interior of the roof, and in communication 20 at one end with the interior of the building, within the wall and roof and at the other end in communication with the outside of the building.
- 25 2. A building comprising a hollow wall

perforated about the outside near its bottom, a hollow roof supported upon said wall in communication with the interior thereof, a tube projecting through said roof, in communication intermediate its ends with the interior of the roof, and in communication 30 at one end with the interior of the building, within the wall and roof and at the other end in communication with the outside of the building, a damper within said tube intermediate its communication with the interior of the hollow roof, and the interior of the building.

3. A building comprising hollow walls perforated about the outside near the bottom and a hollow roof in communication 35 therewith, a ventilating tube within the roof leading from the interior of the building to the outside, a communication in the wall of said tube intermediate its ends with the interior of the hollow roof, a damper within said tube, intermediate its communication 40 with the interior of the hollow roof, and the interior of the building.

ALBERT E. DE ARMOND.
